UNITED STATES PATENT OFFICE.

RICHARD E. SCHULTZ, OF DETROIT, MICHIGAN.

SEAT-BACK SPRING.

1,152,230.

Specification of Letters Patent. Patented Aug. 31, 1915.

Application filed December 21, 1914. Serial No. 878,277.

To all whom it may concern:

Be it known that I, RICHARD E. SCHULTZ, a citizen of Canada, residing at Detroit, in the county of Wayne and State of Michigan, have invented a new and useful Seat-Back Spring, of which the following is a specification.

This invention relates to seat-back springs for vehicles, especially for automobile tonneaus, and the object of the invention is to provide very cheaply means whereby particularly the upper part of the seat-back shall be rendered soft and resilient, and whereby the upholstering material necessarily used may be rendered a minimum; also to provide a construction in which lateral stresses caused by the swinging of the upper parts of the bodies of the various users may be transferred laterally across the spring and yet may be largely taken up before reaching that part of the spring opposite an adjacent user, whereby unnecessary fatigue of the latter is avoided.

The invention consists in the details of construction shown, described and particularly pointed out in the claims.

Certain features of the present invention are quite similar to those of the construction disclosed in the patent to Schultz and Sweeney, No. 999,678, dated August 1st, 1911, but the present spring is much cheaper than that of the patent, and the spiral springs are better supported.

In the accompanying drawings Figure 1 is a front elevation of a preferred embodiment of the present invention. Fig. 2 is a side view thereof. Fig. 3 is a side view corresponding to Fig. 1 but showing a slight modification of the upper portion. Fig. 4 is a diagrammatic fragmentary front elevation of a modified form of spring. Fig. 5 is a side elevation thereof. Fig. 6 is a diagrammatic fragmentary front elevation of a second modification. Fig. 7 is a side elevation thereof. Fig. 8 is a fragmentary front elevation of a third modification. Fig. 9 is a side view thereof. Fig. 10 is a fragmentary front elevation of a fourth modification. Fig. 11 is a side view corresponding to Fig. 10. Fig. 12 is a fragmentary front elevation of a fifth modification. Fig. 13 is a side view thereof. Fig. 14 is a fragmentary front elevation of a sixth modification and Fig. 15 is a side view thereof.

Similar reference characters refer to like parts throughout the several views.

Referring to Figs. 1 and 2, 1 indicates the upper portion of the frame of a seat-back of ordinary construction. This frame has extending across it at about the height 60 of the shoulders of the average user a cross-bar 2, and rising from the latter at intervals are the strips 3, across the upper ends of which extends a second cross-bar 4. The cross-bars 2 and 4 and the strips 3 may each 65 be formed of a flat piece or bar of metal, and they may be riveted or otherwise secured together at points of contact to constitute a frame for the spring construction. As shown in Fig. 2, the strips 3 may be bent 70 backwardly at the points 5 to extend over the upper edge of the frame of the seat-back, after which they may again be bent upwardly at the point 6 and extend outwardly a short distance as indicated at 7; 75 in Fig. 3, however, the strips extend straight upwardly along the seat-back frame until they reach the upper forward edge of the latter, or substantially this position.

Rising from the bar 2 at intervals is a series of spiral springs 10 that may be of the double conical type, the upper turns of the outermost springs preferably being connected to the ends of the bar 2 by the small coiled springs 11 (not shown in Figs. 2 and 85 3). The springs 10 are joined to the upper cross-bar at points laterally displaced from the vertical plane through the corresponding spring by the diagonal arched springs 12 that may be connected to the 90 cross-bar 4 in any desired manner; for example, by tangs 13 struck from the bar and bent over laterally around the spring. It will be noticed that in the constructions shown, but one of these springs 12 is provided for each one of the outer springs 10, while there are two for each one of the intermediate springs 10, whereby the latter are more securely braced against movement 95 in either direction crosswise of the seat-back. It is obvious, however, that if desired, a second diagonal spring may also be provided for each of the end springs. The details of the springs 12 may be varied considerably, but I prefer to use flat ribbons 100 that may be formed by bending an ordinary wire first in one direction and then another in a single plane, as indicated in Fig. 1. At points where the diagonal springs cross each other, they may be joined by wire clips 15, 110 and they may be bent, if desired, around the periphery of the upper ends of the interme-

diate springs 10, as indicated at 16, and connected thereto by clips 17. The particular details of these clips are, of course, subject to considerable variation, as is the shape 5 and position of the tangs 13, but it is desirable to locate the latter vertically above the corresponding spiral springs and to make them of a width great enough to give a substantial base to the ends of the arched 10 springs, whereby any tendency of said arched springs to twist may be overcome. It is also desirable in certain instances to connect the upper ends of the outer springs 10 to the cross-bar 4 by an arched spring 15 18 (of the same general type as the springs 12) that may extend in a vertical plane and connect to the tang 13 directly above the corresponding spiral spring 10.

The modified spring construction, Figs. 4 20 and 5, differs from that heretofore described merely in that the flat arched springs 12 are replaced by spiral springs 20; and in the modification shown in Figs. 6 and 7, the latter are in turn replaced by thin resilient 25 strips 21. It will be obvious that the upper ends of the frame may, in either instance, be bent backwardly in a manner similar to that shown in Fig. 2 if desired. These figures serve also to indicate very generally 30 the relation of the spring construction to the seat frame, in that the bottom 22 of the frame is shown as well as the back 1.

In the embodiment of my invention shown 35 in Figs. 10 and 11, the bars 25, corresponding to the bars 3, are continued downwardly past the longitudinal bar 2 and have their ends joined by a third longitudinal bar or strip 26. The arched springs 27, whose function is similar to that of the springs 12, are 40 in this instance continued downwardly over the row of coil springs 10, and have their lower ends secured to the bar 26, preferably by tangs 28, similar to the tangs 13. If desired, the lower portions of adjacent springs 45 27 may be coupled together by clips 29; and the springs may be joined at crossing points by wires (not shown) corresponding to the wires 15. It will be seen that, in this construction, the coil springs are more securely 50 braced than those shown in Figs. 1 to 7, inclusive, but it is clear that the arched springs and frames of the former might also be extended below the cross-bar 2.

Figs. 8 and 9 indicate one way in which 55 the present invention may be applied to a spring construction having two rows of spiral springs 10. As shown therein, the arched springs 12 are continued downwardly at 31 past the front ends of the upper and 60 lower rows of spiral springs, being wired or otherwise secured thereto at points 32, and are finally anchored to the lower cross-bar 33 of the frame at 34. Instead of the two portions 31, single strands 35 may join the spiral 65 springs together, and the spiral

springs of the lower row may be connected to the lower cross-bar by the strands 36, as indicated in dashed lines, Fig. 8.

The ends pieces 3, Figs. 12 and 13, are joined by an intermediate cross-bar 40 from 70 which a row of auxiliary spiral springs 41, preferably of less strength than the springs 10, rise to support the intersections of the arched springs. This construction allows the springs 10 to be arranged a greater distance below the upper edge of the seat-back than those heretofore described and yet retains the resiliency of the arch. It is also desirable in certain cases to connect adjacent 75 intersection points by the longitudinal 80 springs 42, whereby the upholstering material is prevented from sagging between the arched springs.

The construction just described is also applied in the modification shown in Figs. 14 85 and 15, but, instead of terminating at the first row of springs 10, the frame is continued downwardly as shown in Fig. 8 and is provided with a second intermediate cross-bar 44. The lower ends of the springs 90 12 are, in this instance, bent around the sides of the upper row of springs 10 and secured thereto by clips 45, after which they are extended diagonally downward to adjacent springs 10 of the lower row, being secured thereto by clips 46 and finally anchored to the lower cross-bar 33 by the tangs 34. The intersections of the wires 12 between the rows of springs 10 may be supported by the auxiliary spiral springs 47 that rise from 95 the cross-bar 44 and correspond in strength to the springs 41.

It will be noted that the springs 41 are shown in each case substantially perpendicular to the curvature of the arch at the intersection point: they may be arranged perpendicular to the frame. It is obvious also that the frames shown in Figs. 12 to 15 inclusive may be extended upwardly along 100 the seat-back in the manner indicated in Fig. 3 instead of being offset at the points 5.

The various arched springs resiliently hold the upper ends of the spiral springs in position to take the principal thrusts which the construction receives and they transfer 115 the horizontal components of these thrusts laterally across the seat for some distance, whereby they are gradually absorbed. The arched springs also constitute a direct resilient support for the heads and necks of the users, and together form a surface upon which the upholstering material may be spaced from the frame of the seat-back, whereby a considerable saving in upholstering 120 material results over the amount required where no arches are used.

It is clear that many changes may be made in the details of construction without departing from the spirit of my invention: for example, the angle at which the arched 130

springs are inclined may be varied. I do not, therefore, wish to be limited otherwise than as indicated by the subjoined claims.

I claim:-

- 5 1. In combination with the frame of a seat-back, a seat-back-spring construction comprising a frame formed of longitudinal and transverse bars secured together, a row of coil springs projecting forwardly from the 70 last-mentioned frame in a plane somewhat below the upper edge of the first mentioned frame, and a series of arched springs extending from the outer ends of the coil 75 springs and connected to the frame of the spring at points in proximity to the edge of the frame of the seat-back, some of the series that extend from the upper ends of the intermediate members of the row being inclined in one direction from a vertical plane passing through the corresponding member, and others of the series extending from the upper ends of the same springs in planes inclined in the opposite direction from the 80 corresponding vertical planes, and crossing the oppositely inclined arched springs that extend from the adjacent coil springs in the row, and means for securing the arched springs together at the crossing points 85 whereby they are caused to mutually co-operate in carrying lateral stresses to which the coil springs are subjected.
2. In combination with the frame of a seat-back, a seat-back-spring construction comprising a frame formed of longitudinal and transverse bars secured together, a row of coil springs projecting forwardly from the last-mentioned frame in a plane somewhat below the upper edge of the first mentioned frame, and a series of arched springs extending from the outer ends of the coil 90 springs and connected to the frame of the spring at points in proximity to the edge of the frame of the seat-back, some of the series that extend from the upper ends of the intermediate members of the row being inclined in one direction from a vertical plane passing through the corresponding member, and others of the series extending from the upper ends of the same springs in planes inclined in the opposite direction from the 95 corresponding vertical planes, and crossing the oppositely inclined arched springs that extend from the adjacent coil springs in the row, and means for securing the arched springs together at the crossing points 100 whereby they are caused to mutually co-operate in carrying lateral stresses to which the coil springs are subjected.
3. A seat-back-spring construction comprising a frame formed of longitudinal and transverse bars secured together, a row of coil springs projecting forwardly from the frame in a plane somewhat below the upper level of the seat-back to which it is to be secured, and a series of arched ribbon 105 springs connecting the forward portion of the coil springs to the upper end of the frame, some of said arched springs being arranged in planes inclined to the plane through the axes of the members of the row 110 of coil springs.
4. In combination with the frame of a seat-back, a seat-back-spring construction comprising a frame formed of longitudinal and transverse bars secured together, a row of coil springs projecting forwardly from the last-mentioned frame in a plane somewhat below the upper edge of the first mentioned frame, a series of arched springs extending from the outer ends of the coil 115 springs in planes inclined to the plane passing through the axes of the members of the row of coil springs and being connected to the frame of the spring at points in proximity to the edge of the frame of the seat-back, and a row of auxiliary coil springs projecting from the frame and supporting the arched springs at points intermediate of the ends of the respective arches.
5. In combination with the frame of a seat-back, a seat-back-spring construction comprising a frame formed of longitudinal and transverse bars secured together, a row of coil springs projecting forwardly from the last-mentioned frame in a plane somewhat 120 below the upper edge of the first mentioned frame, a series of arched springs extending from the outer ends of the coil springs and connected to the frame of the spring at points in proximity to the edge of the frame 125
6. In combination with the frame of a seat-back, a seat-back-spring construction comprising a frame formed of longitudinal and transverse bars secured together, a row of coil springs projecting forwardly from the last-mentioned frame in a plane somewhat 130 below the upper edge of the first mentioned frame, a series of arched springs extending from the outer ends of the coil springs and connected to the frame of the spring at points in proximity to the edge of the frame 135
7. In combination with the frame of a seat-back, a seat-back-spring construction comprising a frame formed of longitudinal and transverse bars secured together, a row of coil springs projecting forwardly from the last-mentioned frame in a plane somewhat 140 below the upper edge of the first mentioned frame, a series of arched springs extending from the outer ends of the coil springs and connected to the frame of the spring at points in proximity to the edge of the frame 145

of the seat-back, some of the series that extend from the upper ends of the intermediate members of the row being inclined in one direction from a vertical plane passing 5 through the corresponding member, and others of the series extending from the upper ends of the same springs in planes inclined in the opposite direction from the corresponding vertical planes, and crossing 10 the oppositely inclined arched springs that extend from the adjacent coil springs in the row, and a row of auxiliary coil springs projecting from the frame and supporting the arched springs at points intermediate of the 15 ends of the respective arches.

8. In combination with the frame of a seat-back, a seat-back-spring construction comprising a frame formed of longitudinal and transverse bars secured together, a row 20 of coil springs projecting forwardly from the last-mentioned frame in a plane somewhat below the upper edge of the first mentioned frame, a series of arched springs extending from the outer ends of the coil 25 springs in planes inclined to the plane passing through the axes of the members of the row of coil springs and being connected to the frame of the spring at points in proximity to the edge of the frame of the seat- 30 back, and a row of auxiliary coil springs projecting from the frame and supporting the arched springs at points intermediate of the 35 ends of the respective arches, said auxiliary springs being substantially perpendicular to the curvature of the arch at the point of contact.

9. In combination with the frame of a seat-back, a seat-back-spring construction comprising a frame formed of longitudinal 40 and transverse bars secured together, a row of coil springs projecting forwardly from the last-mentioned frame in a plane somewhat below the upper edge of the first mentioned frame, and a series of springs extending 45 from the outer ends of the coil springs in planes inclined to the plane passing through the axes of the members of the row of coil springs and being connected to the frame of the spring at points in proximity 50 to the edge of the frame of the seat-back.

10. In combination with the frame of a seat-back, a seat-back-spring construction comprising a frame formed of longitudinal and transverse bars secured together, a row 55 of coil springs projecting forwardly from the last-mentioned frame in a plane somewhat below the upper edge of the first mentioned frame, and a series of springs extending from the outer ends of the coil springs 60 and connected to the frame of the spring at points in proximity to the edge of the frame of the seat-back, some of the series that extend from the upper ends of the intermediate members of the row being inclined in one direction from a vertical plane passing 65

through the corresponding member, and others of the series extending from the upper ends of the same springs in planes inclined in the opposite direction from the corresponding vertical planes.

70

11. In combination with the frame of a seat-back a seat-back-spring construction comprising a frame formed of longitudinal and transverse bars secured together, a row of coil springs projecting forwardly from the last-mentioned frame in a plane somewhat below the upper edge of the first mentioned frame, and a series of springs extending from the outer ends of the coil springs and connected to the frame of the spring at 80 points in proximity to the edge of the frame of the seat-back, some of the series that extend from the upper ends of the intermediate members of the row being inclined in one direction from a vertical plane passing 85 through the corresponding member, and others of the series extending from the upper ends of the same springs in planes inclined in the opposite direction from the corresponding vertical planes, and crossing 90 the oppositely inclined springs that extend from the adjacent coil springs in the row, and means for securing the springs together at the crossing points whereby they are caused to mutually coöperate in carrying 95 lateral stresses to which the coil springs are subjected.

100

12. In a seat-back spring construction, the combination of a support, a row of helical springs mounted on the support and projecting forwardly therefrom, and pairs of resilient members extending divergently rearwardly and upwardly from the helical springs to said support to restrain the helical springs from moving laterally and to 105 support upholstering.

13. In a seat-back spring construction, the combination of a support, a series of helical springs mounted on the support and projecting forwardly therefrom, and resilient 110 arches extending upwardly, rearwardly and laterally from the outer ends of said helical springs and connecting to said support to restrain lateral movement of the outer ends of the helical springs and to support uphol- 115 stering.

14. In a seat-back spring construction, the combination of a supporting frame, a row of helical springs mounted on the frame and projecting forwardly therefrom, and a series 120 of resilient members extending from the outer ends of the helical springs upwardly, rearwardly and laterally to said frame, some being inclined in one direction and some inclined in the opposite direction and crossing 125 the others, said resilient members serving to restrain lateral movements of the outer ends of the helical springs and to support upholstering.

15. In a seat-back spring construction, the 130

combination of a supporting frame, a row of helical springs mounted on the frame and projecting forwardly therefrom, a series of resilient members extending from the outer ends of the helical springs upwardly, rearwardly and laterally to said frame, some being inclined in one direction and some inclined in the opposite direction and crossing the others, said resilient members serving to restrain lateral movements of the outer ends of the helical springs and to support upholstering, and springs to support the resilient members at their points of crossing.

16. In a seat spring construction, the combination of a support, a row of helical

5 springs mounted on the support and projecting outwardly therefrom, and pairs of resilient members extending divergently laterally and backwardly from the outer ends of the helical springs to said support to restrain the helical springs from moving laterally and to support upholstering.
